UNITED STATES PATENT OFFICE

ARTHUR M. KIRKWOOD, OF PORTLAND, OREGON

DEBARKING MACHINE

Application filed July 13, 1931. Serial No. 550,530.

My invention relates to debarking machines, especially adapted for removing the bark from logs of considerable size and hence weight.

5 In the debarking of such logs, one method quite generally employed is to bring the log into position for being operated upon by the debarking element and to rotate the log and at the same time move the debarking element 10 longitudinally of the log, whereby the bark is removed from all sides of the log.

However, the machines heretofore provided for this purpose have not been satisfactory for the reason that the means provided, if any, for positioning the log for being operated upon by the debarking elements, were either not strong enough to support the considerable weight of the log and consequently were frequently broken and shut 20 down for repairs, or required so much power for their operation as to render their use impracticable. Further, such means have not been adapted for handling logs of irregular shape or which are bowed, thus requiring 25 selected timber and the rejection of otherwise sound logs.

The object of my invention is therefore to provide a debarking machine having log carrying elements especially adapted to receive 30 a log of considerable size, and hence weight, from the loading platform, to position the log relatively to the debarking element and to simultaneously rotate the log so that the said debarking devices may operate upon the entire periphery of the log and finally to discharge the log from the machine when the debarking operation is completed.

A further object of my invention is to provide a debarking machine provided with log 40 carrying elements, which is economical of manufacture and strong and relatively simple in construction, whereby to assure continuous and rapid operation without breakdowns or other interruptions to the work.

45 A still further object of my invention is to

provide a debarking machine having log carrying elements which are independently operable for handling logs of irregular shape or which are bowed, and capable of being operated with a minimum consumption of 50 power to handle the logs rapidly and expeditiously with only a minimum loss of time in bringing the log into position to be operated upon and to discharge the log when the debarking operation is completed. 55

It is to be noted that if the log carrying elements are not independently operable so as to follow the contour of an irregularly shaped log and support it at all points, as it rotates, that the log will tend to rotate at an irregular 60 rate and will at times tend to twist itself off the log supporting elements. In the former instance causing the debarking element to miss a portion of the periphery of the log and hence not remove all the bark. 65

I attain these objects in a debarking machine in combination with a loading element and a debarking element, a plurality of operative log carriers, each comprising a series of sprockets, one thereof being driven, 70 a pivoted lever arm carrying one of said sprockets and an endless log carrying chain running on said sprockets, said lever arm adapted to place said sprockets and the chains thereby carried in three positions, in one of 75 which said chain is arranged to permit the log to be received from the loading element, the second position of said arm adapted to arrange the sprocket chains so as to lift and hold the log in operative contact with the 80 debarking element, and the third position of said arm positioning said sprocket chains to discharge the log, means for moving said arm, manually controlled means for rotating said arm in either direction. 85

These and other incidental features of my invention, the details of construction and mode of operation are hereinafter fully described with reference to the accompanying drawings. 90

In the drawings:

Figure 1 shows an end elevation of my debarking machine and illustrates the relative arrangement of the parts and a number of logs in position thereon;

5 Figure 2 shows a plan view of the same;

Figure 3 shows a side elevation of my debarking machine looking in the direction of the arrow 3 of Figure 1, with portions broken 10 away to illustrate the debarking element in 15 operation upon a log;

Figure 4 shows an enlarged view of the log carrying elements with a log in position thereon;

15 Figure 5 shows a perspective view of one of the supplemental cross members removed from the machine, by which one section of the log carrying chain is supported;

20 Figure 6 shows a perspective view of one of the lever arms removed from the machine;

Figure 7 shows a fragmentary section taken on the line 7—7 of Figure 4;

25 Figure 8 shows a fragmentary plan view of the log carrying elements illustrated separately from my machine.

Referring now to the figures: My debarking machine comprises a supporting frame *a*, see Figure 1, having at one side a guideway *b* upon which the log is conveyed to the 30 machine by means of a conveyor chain *c* running over driven sprockets *e*. A loading platform *f* is provided at the side of the guideway *b* on which are provided transversely moving conveyor chains *g* mounted over sprockets *h*, *i*. The chain *g* is driven 35 by a motor *k*. A "kicker" element *m* is provided in the guideway *b*, operable preferably by a steam or air cylinder *o* to move the log over onto the chains *g* of the loading platform, see Figure 1.

40 The other side of the loading platform *f* is inclined as at *f'* and is provided with stop dogs *q* operable by a steam or air cylinder *r*.

45 By releasing the stop dog *q* the log will be permitted to roll down the incline *f'* onto the log carrying elements. The log carrying element comprises a series of spaced, transversely arranged lever arms 2, pivoted intermediate their ends on shaft sections 3, mounted in the frame *a*.

50 Supplementary transverse members *a'* are provided having a concaved upper surface *a'*, see Figures 4 and 5, on each side of the lever arm 2. Sprockets 4, 5 are journaled on the frame *a*, the latter on stub shafts 7 and the former on a shaft 6, driven by a motor 10 through suitable connections 11.

55 Sprockets 13 are journaled on stub shafts 60 14 carried by the supplementary member *a'* and sprockets 15 are carried by the upper ends of the lever arms 2, journaled on stub shafts 16.

Slack log carrying chains 20 are mounted 65 over the said sprockets, see Figure 4, and

thus a log having been positioned on said chains is held in the slack portion thereof and rotated counter-clockwise by the lengthwise movement of the chains 20 in the opposite direction.

70

The means for positioning the lever arms 2 so as to successively receive the log to bring it into position with the debarking element, and to finally discharge it when the debarking operation is completed are as follows: 75

The end of each lever arm 2 opposite to that carrying sprocket 15 is connected to a chain running over sprockets 26, 27 carried by the frame *a* and arranged underneath the said lever arms 2. The sprockets 27 are 80 mounted on the shafts 27a and are driven by individual motors 28, operatively connected thereto by suitable devices 29.

By this construction the lever arms 2 may be moved individually to accommodate irregularities and slightly bowed logs and simultaneously for positioning the log relatively to the debarking elements by means of suitable master switches, not shown.

85 As illustrated in Figure 4, the position of the lever arms 2 for receiving the log, is shown by the broken lines *x*, the second position of the lever arms 2 for bringing the log into position to be operated upon by the debarking elements is shown by the full lines 90 and the final position for discharging the logs is shown by the broken lines *y*. Such movement is attained by the operation of the said chains 25 in the direction shown by the arrows and the discharging operation of the 100 log is facilitated by the lengthwise movement of the log carrying chains 20, which tend to roll the log over the high points of the chains formed by the sprockets 13.

When the log is discharged it is received 105 on guideway 50 similar to the guideway *b* before described for carrying the debarked log way.

Limit switches 30 operable by lugs 25a on the chain 25 are shown connected in the circuits 30a of the motors 28 to prevent the accidental operation of the chains too far in either direction, which might break the chains or said lever arms.

110 The debarking element provided comprises a rotary cutter head 40 having blades 41 which is carried by a longitudinally movable swinging frame 42 supported on a carriage 43. The carriage 43 is movable longitudinally of the log on an elevated track 44 supported on a super-structure 45. The cutter head is driven by a motor 46 carried by the said swinging frame 42 and the carriage 43 is driven on its track 44 by a motor 47 mounted thereon.

115 From the foregoing description of the various parts of the device, the operation thereof may be readily understood. Figure 2 shows how the logs are fed in the direction 120 of their length along the trough *b* by means 125

of the chain *c* until the log is in proper position. The log is now moved laterally from the trough *b* by the kicker element *m*, and the log is received on the chains *g*. The 5 chains move the log transversely until it strikes the stop dogs *q*.

As clearly shown in Figure 1, a number of logs may be received on the chains *g* at one time. These logs are fed one by one on to 10 the movable bed 20, and this movement is controlled by the stop dogs *q*. The sprocket 15 for each chain 20 is lowered into the position *x*, shown in Figure 4, when receiving a log. The stop dogs *q* are released long 15 enough to permit one log to roll by gravity to the fixed bed 22. The dogs *q* stop the next log from moving on to the bed until the operator so desires. The sprockets 15 are now moved upwardly into the full-line position, 20 shown in Figure 2, and this is accomplished by the chains 25, which swing the levers 2. The log by this movement is lifted from the fixed bed and is supported by the movable bed. Lengthwise movement is now imparted 25 to the chains 20, and this will revolve the log in a counterclockwise direction. During the rotation of the log, the cutter head 40 removes the bark.

At the completion of this operation, the 30 chains 25 are moved further in the direction of the arrows shown in Figure 4, and the sprockets 15 are raised into the dotted-line position shown at *y*. This will cause the log to roll off from the movable bed and on to 35 the trough 50 where it can be conveyed away by a chain running along the length of the trough. The lengthwise movement of the chains 20 aid in moving the log from the movable bed when the sprockets 15 are raised 40 into the position shown by the dotted lines *y*. The machine is now ready for the next log, and the same operation is repeated.

While I have shown and described only one form of my invention, it will be understood that changes and modifications may be made within the scope of the claims attached hereto without departing from the spirit of the invention, and particularly it should be understood that the term chain used in the 50 specification and in the claims is intended to cover equivalent elements such as flexible members, cables, ropes and rolling elements where the function called for allows of the substitution of such equivalent.

55 I claim:

1. In a log turner, a log supporting means comprising a chain having means for supporting a section thereof at spaced points with a slack in said section on which the log 60 may be received, means for lowering only one of the points for allowing the log to be rolled thereover and means for imparting endwise movement to the chain.

2. In a log turner, a log supporting means 65 comprising a chain having means for sup-

porting a section thereof at spaced points with a slack in said section on which the log may be received, means for raising only one of the points whereby the log may be rolled over the other point and means for imparting endwise movement to the chain. 70

3. In a log turner, a log supporting means comprising a chain having means for supporting a section thereof at spaced points with a slack in said section on which the log may be received, means for raising and lowering only one of the points for facilitating the loading and the discharging of the log and means for imparting endwise movement 75 to the chain. 80

4. In a log turner, a fixed concave bed for the log and a chain having a fixed support disposed slightly above the bed and a movable support for presenting a slack section adjacent the fixed bed and means for moving the movable support whereby the slack section is moved vertically below or above the greater portion of the fixed bed. 85

5. In a log turner, an endless chain having 90 four sprockets supporting the same with a slack in the chain between two of said sprockets and means for lowering and raising one of the latter sprockets all of the other sprockets being rotatable about fixed axes.

6. In a log turner, an endless chain having 95 a plurality of sprockets supporting the same with a slack in the chain between two of said sprockets and a lever for supporting one of the latter sprockets for raising and lowering it. 100

7. In a log turner, an endless chain having a plurality of sprockets supporting the same with a slack in the chain between two of said sprockets and a lever for supporting one of the latter sprockets with a second chain for 105 positively swinging the free end of the lever in either direction.

8. In a log turner, an endless chain having a plurality of sprockets supporting the same with a slack in the chain between two of said sprockets and a lever for supporting one of the latter sprockets, a second endless chain below the first chain and fastened to the free end of the lever and means for imparting endwise motion to the chain in either direction whereby the lever is operated. 110

9. In a log debarking machine, a chain having means for supporting the same at spaced points with a slack formed between the points for supporting a log, one of the points being higher than the other and a cutter mounted for acting on the log in juxtaposition to the higher point. 115

10. In a log debarking machine, an endless chain having means for supporting the same at two spaced points with a slack between the points adapted to receive a log thereon, one of the points being higher than the other, means for imparting endwise movement to 125 130

the chain and a cutter active on the log in juxtaposition to the higher point.

11. In a debarking machine, in combination with a loading and a debarking element, an endless driven log carrying chain and supporting elements therefor including a movable supporting element adapted to arrange a section of said chain consecutively in position to receive the log from said loading element, then to lift and hold the log in operative contact with the debarking element and then to discharge the log from said carrying chain.

12. In a log debarking machine, an endless chain, means for supporting the same so as to form a bed for a log and including one movable member, manually controlled means for moving said movable member for varying the slack in the chain and automatic means for limiting the movement of said movable member.

13. In a log debarking machine, a plurality of endless chains, means for supporting the same in spaced and parallel relation with slack portions of the chains registering to form a bed for a log, such supporting means for each chain including a movable member, and independent means for moving the same which independent means raise and lower the slack portions of the respective chains.

14. A log debarking machine comprising a movable concave bed for the log, said bed consisting of a plurality of chains having slack portions for receiving the log, chain-supporting sprockets, one sprocket in each chain being adjustable for altering the slack in the chain and a cutter engageable with the log at a point diametrically opposite to the adjustable sprocket.
